UNITED STATES PATENT OFFICE.

THOMAS McC. SIMCOE, OF ALLENtown, PENNSYLVANIA.

DESIGN FOR A LID-LIFTER.

SPECIFICATION forming part of Design No. 24,340, dated May 28, 1895.

Application filed January 28, 1895. Serial No. 536,494. Term of patent 7 years.

To all whom it may concern:

Be it known that I, THOMAS MCC. SIMCOE, of Allentown, in the county of Lehigh and State of Pennsylvania, have invented a certain new and useful Design for Household Implements or Tools; and I do hereby declare the following to be a full, clear, and exact description of the invention, such as will enable others skilled in the art to which it pertains to make and use it, reference being had to the accompanying drawing, which forms part of this specification.

My invention relates to designs for stove lid lifters illustrated in the accompanying drawing, which is a perspective view thereof.

A is the handle having an intermediate swelled portion G with the converging lines

H, and at its outer end with the curved projection C. Below the curved projection C is the laterally projecting portion D having its outer face provided with the groove E and at each side thereof the transverse configuration F.

Having thus described my design, what I claim, and desire to secure by Letters Patent, is—

The design for a stove lid lifter substantially as herein shown and described.

In testimony whereof I affix my signature in presence of two witnesses.

THOMAS McC. SIMCOE.
